STUDIO COUCH

William W. Wilson, Memphis, Tenn.

Application April 23, 1943, Serial No. 484,234

5 Claims.

(Cl. 5—47)

This invention relates to studio couches which are to be used, at option, as sofas or beds and in which a seat portion and a back portion are hinged together and are shiftably secured to a supporting base or frame by arms, through which shift of the seat and back relatively to the base is accomplished in changing from sofa to bed, or vice versa.

It particularly relates to means for latching the back to the seat, to hold the back in upright position when the structure is used as a sofa, and to accomplish movement of the back to bed position, and to means for tripping and releasing the latch by over-travel of the seat when the back has reached bed position, and is a continuation in part and improvement on my co-pending application for patent, Serial No. 481,810, filed April 6, 1943, which became Patent No. 2,357,441 on September 5, 1944.

The objects of the present invention are:

To provide a brace or latch which will solidly brace between the back and seat when the back is in upright position, and which, when in such bracing position, will be locked against accidental displacement;

To provide locking means in connection with such a latch or brace which will automatically release the latch on over-travel of the seat after the back has been shifted to bed position, to allow return of the seat to bed position, and which will effectually prevent re-engagement of the latch during return movement of the seat from such over-travel position to bed position; and

To generally improve the detail and construction of such structures.

The means by which the foregoing and other objects are accomplished, and the manner of their accomplishment, will readily be understood from the following specification upon reference to the accompanying drawings, in which:

Fig. 1 is an end elevation of the base, the seat, and a portion of the back, with parts of each thereof broken away, and with the latch and bracing structure shown partially in section and partially in elevation, the back and seat being shown latched and braced in respective seat and back position.

Fig. 2 is a fragmentary sectional elevation taken on the line II—II of Fig. 1.

Fig. 3 is a transverse sectional elevation of the base and back and a fragmentary portion of the seat, showing the back turned into bed position on the base, and the position of the seat when this is accomplished, and showing in dotted lines

the release of the latch accomplished by over-travel of the seat beyond the position shown.

Fig. 4 is an enlarged longitudinal section of the latching end of one of the braces.

5 In these drawings all cushions and upholstery have been omitted, supporting frame work only being shown.

Referring now to the drawings in which the various parts are indicated by numerals:

10 11 is a rectangular base having feet 13, which base supports a seat and back structure, both seat and back being of the same length as the base.

15 The seat frame comprises a pair of ends 15 which overlie and are adapted to rest on the opposite ends 17 of the base. The ends 15 are rigidly connected by longitudinal members 19, 21, respectively adjacent the front and rear of the ends.

20 The back frame comprises a pair of ends 23, which align with the ends of the seat and are similarly rigidly connected by longitudinal members 25 and 27.

25 Secured on the inner sides of the seat frame ends 15 are members 29 which extend rearwardly of the back of the seat frame and overlap the inner sides of the lower, or front, portions of the back frame ends 23, to which they are hingedly secured by hinge pins 31.

30 The hinge pins 31 also serve as hinge pins for arms 33, which extend downwardly and are hinged to the end members 17 of the base by hinge pins 35. Additionally, the ends 23 of the back are connected by hinge pins 37 to arms 39 which extend downwardly and are connected by hinge pins 41, also to the end members of the base. Preferably the opposite ends of the arms 33 and 39 are inwardly cut from their opposite ends to provide slots 43 and are provided with clamping screws 45 to provide means for clamping the arm ends on their hinge pins and maintaining tightness as wear occurs.

35 The hinge pins 35 and 41 are so spaced apart relatively to the length of the arms 33 and 39 and their points of attachment to the seat and back

40 that when the seat 15 is resting on the base 11 in seating position with the back in upright position, the front edge of the seat is substantially flush with the front edge of the base, whereas when the back is turned to bed position, as in Fig. 3, the hinge joint between the seat and back is forwardly shifted and the seat and back are about equally supported by the base with the forward edge of the seat overhanging (not shown) the front of the base and the top or rear edge of the back overhanging the back of the base.

Secured to the lower edge of the longitudinal member 25 of the back is a forked bracket 47 which extends rearwardly therefrom. 49 are blocks secured to the longitudinal member 25 and the bracket to provide bracing means therefor, and 51 are triangular blocks affording additional bracing. 53 are brace members which are pivotally secured by hinge pins 55 to these brackets. 57 are identical forked brackets which are secured to the rear edge of the longitudinal member 21 of the seat and extend downward therefrom. Carried by the extending fork of the brackets 57 are latch pins 59. The brace members 53 extend downwardly and forwardly from the hinge pins 55 and rest on the latch pins 59 when the back is in upright position to brace the back in such position. The forward edges of the notches are sloped to provide raising cams 63 for disengaging the braces from the pins on over-travel movement of the latch.

The forward ends of the braces are slotted rearwardly to provide a forked end having side portions 65 between which are disposed a trip latch 67 which is pivoted on a transversely disposed pin 69. The forward end of the latch is rearwardly notched to form a portion 67-A of reduced depth which engages with and is supported by a block 71 disposed between the sides 65 of the brace.

Below the pin 69 the latch, Fig. 4, is substantially halved in depth so that its under edge 67-B will clear the top of the notch in the brace, the halving extending forwardly of the notch. Forward of the halved portion the latch has a downwardly and rearwardly extending tongue portion 73, the end 73-A of the tongue extending below the under surface of the brace and rearward of the notch, and the underside 73-B of the tongue sloping forwardly and upwardly to a junction with the undersurface of the latch. Forwardly of the pin 69 the upper edge of the latch is notched to provide a shoulder 67-C which is adapted to engage the forward end of a cover plate 75 and limit upward swinging movement of the latch.

In use as a sofa, the seat rests flat on the base 11 with its forward edge substantially flush with the front edge of the base, and with the back hinged to the seat by the pivot pins 31 extending in upright position, and held in such position by engagement of the shoulders 61 of the braces 53 in bracing engagement with the pins 59 carried by the downwardly extending forked members 57.

To shift from sofa position to bed position, the front of the seat is raised about the pins 31 as centers, this raising movement accomplishing a complementary backward movement of the back and through the arms 33 and 39 accomplishing a forward movement of both back and seat with relation to the base 11. Movement is continued until the back rests flat on the base, as shown in Fig. 3, at such time the pins 59 being in firm engagement with the shoulders of the braces 53.

Further movement of the seat is continued, the latch pins 59 moving about the pins 31 as centers to the position 59-X, shown dotted, and the braces moving to the dotted positions 53-X, about the pins 55 as centers. In this movement the sloping shoulders 63-X of the braces raise the brace notches from pin engagement, and the pins 59-X cooperate with the rear sides of the latch trip tongues 73-X to raise the latches to the positions 67-X. On additional movement of the seat upward and backward the latch pins

move along the underside of the latches past the tongues 73-X and allow the latch trips to drop into releasing position. The seat is then swung downwardly until it rests on the base 11. In this downward movement the latch pins are deflected by the tongues 73 of the trips to over-ride the notches 59 and permit the lowering of the seat.

I claim:

1. In a studio couch, including a seat frame, a back frame, and hinge means adjacent the top and front of the respective rear and lower edges of said seat and back, hingedly securing said seat and back together; bracing means for holding said back in upright position relatively to said seat, and for accomplishing shift of said back to bed position, comprising spaced units, each unit including forked brackets, respectively rigidly secured to said seat and extending downwardly, and to said back and extending rearwardly, from said hinge means, a latch pin carried by said seat bracket and spaced below said hinge means, a pivot pin carried by said back bracket and spaced rearwardly from said hinge means, a brace hingedly mounted on said pivot pin and extending downwardly past and resting on said latch pin, said brace adjacent its forward end being abruptly notched to effect a shoulder for bracing engagement with said latch pin, and forwardly of said shoulder, said notch being downwardly and forwardly sloped to effect a disengaging cam, said brace being slotted from its forward end rearwardly beyond said notch, a latch trip housed in said slot, a pin above said notch and rearward thereof extending transversely through said brace and trip to hingedly mount said trip in said slot, the underside of said trip being cut away above said notch from its rear end forwardly of said notch, said trip having a tongue portion forwardly of said notch extending downwardly and rearwardly below the bottom of said latch and across said notch, the under-edge of said tongue sloping forwardly and upwardly to the bottom of said latch.
2. In a studio couch, including a back, a seat, means hingedly securing said seat and back together, and bracing means for holding said back in upright position relatively to said seat, and for accomplishing shift of said back to bed position; each said bracing means including a latch pin carried by said seat, and a brace pivotally secured to said back and riding on said latch pin, said brace adjacent its forward end being abruptly notched to effect a shoulder for bracing engagement with said notch pin, and forwardly of said shoulder, said notch being downwardly and forwardly sloped to effect a disengaging cam; said brace being slotted from its forward end rearwardly beyond said notch, a latch trip housed in said slot, a pin above said notch and rearward thereof extending transversely through said brace and trip to hingedly mount said trip in said slot, the underside of said trip being cut away above said notch from its rear end forwardly of said notch, said trip having a tongue portion forwardly of said notch extending downwardly and rearwardly below the bottom of said latch and across said notch, the under-edge of said tongue sloping forwardly and upwardly to the bottom of said latch.
3. In a studio couch, including a back, a seat, means hingedly securing said seat and back together, and bracing means for holding said back in upright position relatively to said seat, and for accomplishing shift of said back to bed position; each said bracing means including a latch pin

carried by said seat, and a brace pivotally secured to said back and riding on said latch pin, said brace adjacent its forward end being abruptly notched to effect a shoulder for bracing engagement with said latch pin, and forwardly of said shoulder, said notch being downwardly and forwardly sloped to effect a disengaging cam; a latch trip pivotally secured to said brace adjacent and above said shoulder, and means limiting downward movement of the forward end of said trip, the underside of said trip being cut away above said notch from its rear end forwardly of said notch, said trip having a tongue portion forwardly of said notch extending downwardly and rearwardly below the bottom of said latch and across said notch, the under-edge of said tongue sloping forwardly and upwardly to the bottom of said latch.

4. In a studio couch, including a back, a seat, means hingedly securing said seat and back together, and bracing means for holding said back in upright position relatively to said seat, and for accomplishing shift of said back to bed position; each said bracing means including a latch pin carried by said seat, and a brace pivotally secured to said back and riding on said latch pin, said brace adjacent its forward end being abruptly notched to effect a shoulder for bracing engagement with said latch pin, and, forwardly of said shoulder said notch being downwardly and forwardly sloped to effect a disengaging cam; a latch trip, means adjacent said shoulder pivotally securing the rear end of said trip to said latch,

and means limiting downward movement of the forward end of said trip, the underside of said trip being cut away above said notch, said trip having a tongue portion forwardly of said notch extending downwardly and rearwardly below the bottom of said latch and across said notch, the under-edge of said tongue sloping forwardly and upwardly to the bottom of said latch.

5. In a studio couch, including a back, a seat, means hingedly securing said seat and back together, and bracing means for holding said back in upright position relatively to said seat, and for accomplishing shift of said back to bed position; each said bracing means including a latch pin carried by said seat, and a brace pivotally secured to said back and riding on said latch pin, said brace adjacent its forward end being abruptly notched to effect a shoulder for bracing engagement with said latch pin, and, forwardly of said shoulder said notch being downwardly and forwardly sloped to effect a disengaging cam; a latch trip, means adjacent said shoulder pivotally securing the rear end of said trip to said latch, means limiting upward swing of said trip, and means limiting downward movement of the forward end of said trip, the under-side of said trip being cut away above said notch, said trip having a tongue portion forwardly of said notch extending downwardly and rearwardly below the bottom of said latch and across said notch, the under-edge of said tongue sloping forwardly and upwardly to the bottom of said latch.

WILLIAM W. WILSON.
